George J. Winter, INVENTOR

BY
A. J. Sangster.
ATTORNEY.

UNITED STATES PATENT OFFICE.

GEORGE J. WINTER, OF BUFFALO, NEW YORK.

ATTACHMENT FOR DOORS.

SPECIFICATION forming part of Letters Patent No. 634,491, dated October 10, 1899.

Application filed March 20, 1899. Serial No. 709,742. (No model.)

To all whom it may concern:

Be it known that I, GEORGE J. WINTER, a citizen of the United States, residing at Buffalo, in the county of Erie and State of New York, have invented certain new and useful Improvements in Attachments for Doors, of which the following is a specification.

My invention relates to a device comprising an attachment or attachments adapted to be secured to the lower portion of an ordinary door and a roller supported in slideways in said attachment or attachments and adapted to rest upon the floor to prevent the entrance of drafts or currents of air.

For a full understanding of the merits and advantages of the invention reference is to be had to the accompanying drawings and the following description.

The invention is susceptible to various changes in the form, proportion, and minor details of construction without departing from the principle or sacrificing any of the advantages thereof, and to a full disclosure of the invention an adaptation thereof is shown in the accompanying drawings, in which—

Figure 1 is a side elevation of a door having my improved device attached thereto. Fig. 2 is an enlarged edge view of a portion of a door having my invention fastened thereto. Fig. 3 is a longitudinal central section through the roller. Fig. 4 is an enlarged detached view of one of the metallic supporting devices. Fig. 5 is an enlarged detached view of one of the spring-supporting rods, also illustrating a longitudinal section through one of the shafts to show the manner of attaching the rods to the shaft. Fig. 6 is an enlarged side elevation of one of the spring-supporting rods and the shaft to which it is attached.

In referring to the drawings in detail like numerals designate like parts.

My improved device is illustrated in Fig. 1 as attached to an ordinary door 1 and comprises the metallic supporting-plate 2 and the roller 3. Each of the metallic plates 2 is preferably formed of sheet metal stamped into shape, although it may be formed in any other well-known way without departing from the scope of my invention, and has a vertical slot 4 and a longitudinal portion or ear 5, which

is formed integral with the plate and extends therefrom from a point substantially vertical above the slot 4. The upper portions of the plates are bent at substantially right angles and rest against the door side, screws 6 being passed through said portions to fasten the plates thereto. The roller 3 is formed of any well-known material or metal and is provided with a peripheral covering of soft or fibrous material 8—such as carpet, rubber, or cloth. A circular hole 9 extends centrally longitudinally into each end of the roller to form a bearing, and a short horizontal shaft 10 is loosely journaled in each of said holes. An enlargement 11 is formed at the outer end of each of these shafts and is provided with a vertical screw-threaded opening, in which the screw-threaded lower end 12 of one of the spring-supporting rods 13 is adapted to screw. (See Fig. 5.) A slit or slot 14 is cut in the top of each rod to receive a screw-driver or similar instrument. A spiral spring 15 is supported upon each of these rods 13.

The attachment is assembled and fastened to a door as follows: A spiral spring 15 is placed upon one of the spring-supporting rods and the upper end of the rod inserted in an opening through one of the ears 5. The inner end of one of the shafts 11 is passed through the slot in one of the plates 2, and the lower screw-threaded rod is screwed into the screw-threaded opening in the enlarged outer end of the shaft. The other plate and its attachments are assembled in like manner, and one of the plates is attached to the lower surface of the door near one side edge by the screws. The shafts are in the openings in the ends of the roller and the opposite plate is secured in place by screws.

A stop device for limiting the upward movement of the roller is fastened to the door above the roller. This device is preferably fastened as shown in the drawings, in which a vertical plate 16 is secured to the door by the screws 17 and has a curved arm 18, which is adapted to extend over the roller. This device can be easily and quickly attached to any door without altering or appreciably marring the same and serves to prevent the entrance of drafts.

The roller is maintained against the floor with a spring tension, and owing to the slots

in the plate can rise and roll over any small object or obstruction in its path. The covering of fibrous or soft material upon the roller prevents any wearing of the carpet incident to the opening and closing of the door and also acts to clean the portion of the carpet over which it passes.

I claim as my invention—

1. An attachment for doors, comprising two plates having their upper portions bent at an angle and adapted to be secured to the lower portion of a door, and each having a vertical slot in their lower portion and a bent part vertically above said slot forming a horizontal ear, a roller interposed between said plates and having end openings, shafts journaled in said openings and passing through and extending beyond the vertical slots and having vertical extensions on the exterior of the slots passing through openings in the ears and spiral springs loosely mounted on said vertical extensions with their upper ends resting against the ears and their lower ends against the shafts, as set forth.
2. An attachment for doors, comprising two plates adapted to be secured to the lower portion of a door, and each having a vertical slot and an integral outwardly-extending ear, a roller interposed between said plates and having shafts passing through the slots and provided with vertical openings, vertical extensions forming spring-supporting rods having their upper ends supported in the ears and their lower ends detachably secured in the shaft-openings, springs supported upon said rods, and a curved arm attached to the door and extending over the roller to limit its upward movement, as set forth.
3. An attachment for doors, comprising two plates each having a portion bent at substantially a right angle and adapted to be secured to the lower portion of a door, and a main portion provided with an integrally-formed horizontal ear and a vertical slot directly be-

low said ear, a roller interposed between said plates and having shafts projecting through said slots, said shafts having vertical openings in their outer extremes exterior to the slots, vertical rods having their upper ends supported in the ears and their lower ends supported in the shaft-openings, springs mounted upon said rods for maintaining said roller in its lower position with a spring force, and a stop device for limiting the upward movement, as set forth.

4. An attachment for doors, comprising two plates adapted to be secured to the lower portion of a door, and each having a vertical slot and a horizontal ear, a roller interposed between said plates and having end openings, shafts journaled in said openings and having enlarged outer ends provided with screw-threaded openings, spring-supporting rods having their screw-threaded lower ends screwing into the openings in the enlarged ends of the shafts and their upper ends passing through openings in the ears and springs supported on said rods, as set forth.

5. An attachment for doors, comprising two plates adapted to be secured to the lower portion of a door, and each having a vertical slot and a horizontal ear, a roller interposed between said plates and having end openings, shafts journaled in said openings and having enlarged outer ends provided with screw-threaded openings, spring-supporting rods having their screw-threaded lower ends screwing into the openings of the enlarged ends of the shafts and their upper ends passing through the ears, springs supported upon said rods, and a curved arm attached to the door and extending over the roller to limit its upward movement, as set forth.
